[57] CLAIM

The ornamental design for a hand soak tray, as shown and described.

DESCRIPTION

FIG. 1 is a top perspective view of a hand soak tray showing my new design;

FIG. 2 is a left side elevational view thereof, the right side elevational view being a mirror image;

FIG. 3 is a front elevational view thereof;

FIG. 4 is a rear elevational view thereof;

FIG. 5 is a top plan view of the hand soak tray of my new design; and

FIG. 6 is a bottom plan view thereof.

FIG. 1

FIG. 2

FIG. 4

FIG. 3

FIG. 5

FIG. 6
